UNITED STATES PATENT OFFICE.

BINNY FRANK COMBS, OF EAST BERKSHIRE, VERMONT.

IDENTIFICATION-MARKER FOR RECEPTACLES SUCH AS MILK-CANS.

1,348,628.

Specification of Letters Patent.

Patented Aug. 3, 1920.

Application filed August 11, 1919. Serial No. 316,561.

To all whom it may concern:

Be it known that I, BINNY F. COMBS, a citizen of the United States of America, residing at East Berkshire, in the county of 5 Franklin and State of Vermont, have invented Improved Identification-Markers for Receptacles such as Milk-Cans, of which the following is a specification.

Cans or receptacles for milk, cream, etc., 10 under the present conditions of supply are gathered from many different, distant locations and transported to central stations or distributing points, and when emptied must be returned to the owner or place of origin. 15 Heretofore such receptacles have usually been marked for delivery identification, on a tag attached by a string to the handle, or to some other projecting part thereof.

When handling such cans in transportation, particularly large sizes, the tags are 20 frequently torn off and the identification of the consignee and destination of the can is thus lost; also the farmers and creameries are accustomed to keep their cans of milk 25 and cream in tanks of cold or iced water, and when they are to be stored, or to be transported long distances, the cans are usually packed in ice, and then the water softens the paper of the tags and tends to destroy them, 30 and if tied to the handle of the can it is difficult to see the tag when the cans are packed closely together in a car or freight house.

Metal plates bearing the name of the 35 owner have been soldered to the side of cans, as also a bracket or pocket for a card has been attached to the perpendicular side of a box or receptacle for merchandise; but such an arrangement would not be practical for 40 a can for milk, cream, etc., for the reasons above mentioned.

My improvement relates to identification 45 holders and markers for receptacles such as milk cans, and consists of a metal holder for cards, attached to the top part of the can, preferably to the dome-shaped portion above the top hoop, known as the "breast" of the can. This holder has an opening to disclose to view a card or tag inserted therein, which bears designative or descriptive matter, such as the name and address of the consignee, the name, quantity, quality, etc., of the contents of the can, while upon the surface of the holder beyond and around the

card opening, are placed marks and designs 55 to indicate the origin, ownership, number, net weight, etc., of the receptacle, and also the metal around the opening is provided with means located a little back from the edge of such opening, to reinforce the metal 60 of the projecting lip, and to limit the movement of the cards when inserted therein. This may conveniently be accomplished by soldering a wire at the angle between the flat 65 part of the holder and the raised portion 70 around the opening. It will also be found advantageous to produce a projecting bead at the location of this angle, to receive and more securely hold the wire and also to serve as a guard against external blows. 75

Attaching the holder to the curved or beveled surface of the top of the can insures the holding of the cards securely in place therein, into whatever position the can may be dropped, sometimes with the top down, when 75 they are empty and carelessly thrown into a car to be returned to the owner.

The indication marks or designs on the holder around the card opening, instead of being the full name of the owner, may be 80 the initial letter or letters of the name of the owner, or a monogram of those letters, as illustrated in Fig. 4, of the drawings.

In the drawings, forming a part of this specification, Figure 1, is an elevation of the 85 top part of a milk can with my identification marker and holder attached to the dome-shaped breast, with a card inserted in the holder; Fig. 2, is a vertical section of the top of the can and holder, on line 2—2 of 90 Fig. 1; Fig. 3, is an elevation of the reinforcing wire around the raised card holding portion of the marker; Fig. 4, illustrates the holder in the form of a monogram, M.H.F. or it may be made in the form of any other 95 device or ornament and superficially to conform to the contour of the breast of the can.

Referring to the drawings by designating characters, A, is the identification holder, B, the opening therein for exposing the card 100 which bears the descriptive or designating matter, C, is the dome-shaped breast of the can, D, is a reinforcing wire around the card opening, E, is the card for the descriptive matter; in Fig. 2, is shown at D, the projecting bead to receive the reinforcing wire or metal strip. 105

Although it will be found preferable to re-

inforce the metal of the projecting lip of the card holder by a wire or strip of metal, I do not intend to limit my invention to a reinforced lip, as the holder is practically operative without it.

5 I claim:

1. An identification marker for milk cans, consisting of a metal holder for cards, the holder being made to conform superficially 10 to the contour of the dome-shaped top of the can to which it is to be applied, to serve as additional means for holding the cards therein, and having an opening to expose descriptive matter upon the card when inserted; the portion of the marker surrounding said opening being provided with a raised bead at the inner limit of the project-

ing edge to reinforce it against external pressure.

2. An identification marker for milk cans, 20 consisting of a metal holder for cards, the holder being made to conform superficially to the contour of the dome-shaped top of the can to which it is to be applied, the curves thereof serving as additional means for holding the cards therein, and having an opening to expose designative matter when the card is inserted; the portion of the marker surrounding said opening being provided with means secured at the inner limit 25 of its projecting edge in addition to the raised bead thereon to reinforce it and limit the movement of the cards therein.

BINNY FRANK COMBS.
